ATTORNEY

UNITED STATES PATENT OFFICE.

JOHN BERCIK, OF DAISYTOWN, PENNSYLVANIA.

SAFETY RAILROAD JOINT.

Application filed February 19, 1923. Serial No. 620,025.

To all whom it may concern:

Be it known that I, JOHN BERCIK, a citizen of Hungary, residing at Daisytown, in the county of Washington and State of Pennsylvania, have invented new and useful Improvements in Safety Railroad Joints, of which the following is a specification.

This invention relates to a railway joint, the general object of the invention being to 10 provide a chair for holding the abutting ends of a pair of rails, with a wedge member for holding the ends in the chair.

Another object of the invention is to provide rack means for moving the wedge 15 member into and out of operative position with ratchet means for locking the rack means with the wedge member in operative position.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the 30 several views, and in which:

Figure 1 is a plan view of a portion of a track showing the invention in use.

Figure 2 is a section on line 2—2 of Figure 1.

Figure 3 is a section on line 3—3 of Figure 1.

Figure 4 is a bottom plan view.

Figure 5 is a view of a wedge member.

Figure 6 is a section on line 6—6 of Figure 2.

In these views 1 indicates the rails and 2 the ties of a track. A chair 3 is provided for the adjacent ends of rails, said chair being suitably secured to a tie, as shown. The chair 43 is provided with a stationary flange 4 which is shaped to engage a part of the base and a part of the web of each rail and the chair is also provided with the grooved member 5 which is spaced a sufficient distance from 50 the flange to permit the rail ends to be placed upon the chair and in engagement with the flange. The side wall of the groove is inclined, as shown at 6, and this groove is adapted to receive a wedge member 7, the inner part of which is shaped to

engage a part of the base and a part of the web of each rail so that when the wedge member is in place the rail ends will be securely connected with the chair by means of said wedge member and the flange 4. 60

I provide means for moving the wedge member upon the chair, such means consisting of a rack 8 formed on the bottom of the member and a toothed wheel 9 which is carried by a shaft 10 which is journaled in the bottom of the chair. The shaft is provided with a wrench receiving head 11 and with a ratchet wheel 12 which is engaged by a pawl 13. 65

From the above it will be seen that after 70 the rails have been put in position and the wedge member placed with its rack in engagement with the wheel 9 the said wedge member can be moved to a position where it will lock the rail ends upon the chair 75 by turning the shaft by a wrench or the like to cause the wheel 9 to move the wedge member. After the wedge member is forced tightly against the rails it will be held in this position by the ratchet mechanism. 80 When the rails are to be removed it is simply necessary to remove the pawl out of engagement with the ratchet wheel and then turn the shaft in a reverse direction to move the wedge member away from the grooved 85 member. The rails can then be lifted out of the chair.

It is thought from the foregoing description that the advantages and novel features of my invention will be readily apparent. 90

I desire it to be understood that I may make changes in the construction and in the combination and arrangement of the several parts, provided that such changes fall within the scope of the appended claims. 95

What I claim is:

1. A rail joint of the class described comprising a chair having flanges thereon, one of the flanges being grooved, a wedge member engaging the groove and rack means for moving the wedge member into and out of engagement with the rails. 100

2. A rail joint of the class described comprising a chair having flanges thereon, one of the flanges being grooved, a wedge member engaging the groove, rack means for moving the wedge member into and out of engagement with the rails and ratchet means for holding the wedge member in operative position. 105 110

3. A rail joint comprising a chair upon which the rail ends are to be seated, a stationary flange upon the chair for engaging parts of the rails, a grooved projection on the chair spaced from the flange, a wedge member having a part engaging the groove, a rack on the bottom of the wedge member, a shaft journaled in the chair, a toothed wheel carried by the shaft and engaging the rack and ratchet mechanism for holding the shaft against retrograde movement.

In testimony whereof I affix my signature.

JOHN BERCIK.
